(57) **CLAIM**

The ornamental design for a plant aeration device, as shown and described.

DESCRIPTION

FIG. 1 is a top, side exploded perspective view of the plant aeration device;

FIG. 2 is a top, side perspective view of the plant aeration device;

FIG. 3 is a right, side elevation view of the plant aeration device;

FIG. 4 is a left, side elevation view of the plant aeration device;

FIG. 5 is a top plan view of the plant aeration device;

FIG. 6 is a bottom plan view of the plant aeration device; and,

FIG. 7 is a sectional view taken along the lines indicated in FIG. 4.

The broken lines in the drawings depict portions of the plant aeration device, and form no part of the claimed design.
